UNITED STATES PATENT OFFICE.

GEORGE B. ADAMS, OF NEWARK, NEW JERSEY, ASSIGNOR TO THE EAGLE
PENCIL COMPANY, OF NEW YORK.

PENCIL-CLASP.

SPECIFICATION forming part of Letters Patent No. 436,591, dated September 16, 1890.

Application filed August 5, 1890. Serial No. 361,100. (No model.)

To all whom it may concern:

Be it known that I, GEORGE B. ADAMS, of the city of Newark, in the State of New Jersey, have invented a new and useful Improvement in Pencil-Clasps, of which the following is a specification.

My invention consists of a convenient, simple, and very efficient form of pencil-clasp, which can best be explained and understood 10 by reference to the accompanying drawings, in which—

Figure 1 is a perspective view of the device with the button or head thrown back. Fig. 2 is a longitudinal central section of the same, 15 with the button or head closed or shut down and a pencil inserted in the pencil-clasp proper.

The pencil-clasp A itself consists of a piece of sheet metal bent to form the spring closing 20 and expanding pencil-clasping jaws *a*, from below which extends the inwardly-bent spring-tongue *b*, which is adapted to press laterally against the pencil *P* when the latter is inserted in the clasp, as seen in Fig. 2. To this 25 clasp is riveted or otherwise suitably secured the base *c* of a shank *d*, which is hinged at *e* to a button or smooth head *B*, and is provided with a cam or projection *f* at its inner end adapted to bear against a spring-strip *g* in 30 the button or head in such manner that the button shall by the action of the spring be held in either open or closed position when moved by hand to such position. Upon the under face of the button are one or more 35 gripping-teeth *h*, and at the proper point on the base *c* similar teeth *i* are formed, between which and the teeth *h* the part of the garment

to which the holder is applied is grasped when the button is closed or shut down.

The device just described is simple, easily 40 and cheaply constructed, and exceedingly efficient. The button serves to hold the device securely in place on the garment, while by reason of its construction and arrangement it can be most easily applied to and removed 45 from the garment.

In applying the device to the edge of the waistcoat side pocket, for example, the clasp can be on the inside and the button on the outside of the pocket, or vice versa. When 50 on the inside of the pocket, the button offers absolutely no obstacle to entrance into the pocket or to the placing of other objects therein. When on the outside of the pocket, it appears merely as a button and has not the 55 unsightly appearance of other fasteners.

What I claim and desire to secure by Letters Patent, as a new article of manufacture, is—

The hereinbefore-described pencil or clasp, 60 consisting of the clasp *A*, the button *B*, and the shank *d*, secured by its base *c* to the clasp *A* and by a hinge *e* to the button, and provided with a cam or projection *f* to bear against and act with the spring *g* of the button in the manner described, the button and the base being provided with gripping-teeth, 65 substantially as and for the purposes set forth.

In testimony whereof I have hereunto set my hand this 1st day of August, 1890.

GEORGE B. ADAMS.
